J. B. Kendall

UNITED STATES PATENT OFFICE.

J. B. KENDALL, OF BOSTON, MASSACHUSETTS.

IMPROVED HORSESHOE.

Specification forming part of Letters Patent No. 33,709, dated November 12, 1861.

To all whom it may concern:

Be it known that I, J. B. KENDALL, of Boston, in the State of Massachusetts, have invented certain new and useful Improvements in Horseshoes; and I do hereby declare that the following is a full, clear, and exact description of the same, reference being had to the annexed drawings, and to the letters of reference marked thereon, as forming a part of this specification, in which—

Figure 1 represents a side view, in which is shown the mode of constructing and securing the auxiliary shoe. Figs. 2 and 3 represent plan views of the auxiliary and stationary shoe.

The nature of my invention consists not in the employment of an adjustable plate or screw-calks, as both in various modifications have been used, but in the peculiar mode of constructing the auxiliary shoe and the employment of it in combination with the stationary shoe and screw-calks, all being arranged as will be hereinafter fully set forth.

To enable others skilled in the art to make and use my invention, I will now proceed to describe its construction and mode of operation.

A represents the stationary shoe, which is provided at its curve with the hole b, the advantage of which will be more fully appreciated hereafter.

a a represent four female screws located as exhibited in Fig. 3.

It will be observed that the stationary shoe has no heel-pieces or calks, but in all other respects save those which have been mentioned is precisely similar to the ordinary horseshoe.

B represents the lower half or auxiliary shoe, and should correspond in size with the upper portion, A, though it is not necessary that it should be quite so thick.

d is a pin which is securely riveted on the under side of part B. This pin is designed to fit snugly in the hole b when the two parts are placed together, thus preventing all possibility of slipping or of too much strain coming upon the screw-calks, which will be referred to pres-

ently. The auxiliary shoe B must be provided with holes corresponding in locality with the female screws in shoe A.

f and g g represent the front and hind or heel calks. Said calks should be formed with the shoe—something similar to the ordinary shoe, though larger and more tapering, as fully seen in Fig. 1.

h h represent the screw-calks, which taper from a square almost to a point, as exhibited in Fig. 1. The object in having their heads square is to facilitate removing and replacing them by means of a wrench.

The peculiar advantage of this invention is—viz., the two parts are so constructed with relation to each other that, whether separate or combined, they form a perfect shoe in every essential particular, suitable to the circumstances which would make them desirable. Another advantage which I might also mention is the ease and rapidity with which a horse may be rough-shod.

It would be well to remark that my invention is designed more particularly for army purposes, where it is frequently necessary that a horse should be rough-shod at a moment's notice. By being provided with shoes of the character I have described an officer or rider may at any time so shoe his horse as will enable him to travel the most perilous journey with safety.

The operation is as follows: The stationary shoe A being put on in the ordinary way, the auxiliary shoe B is properly adjusted, and the calks h h screwed home by means of a wrench.

Having thus fully described my invention, what I claim, and desire to secure by Letters Patent, is—

The auxiliary shoe B, when provided with permanent heel and toe pieces f and g g, in combination with stationary shoe A, both parts being secured together, substantially as and for the purpose set forth and described.

J. B. KENDALL.
